Primary Examiner — Jonathan J Han

(74) *Attorney, Agent, or Firm* — Knobbe, Martens, Olson & Bear, LLP

(57) **CLAIM**

The ornamental design for a bicycle shoe, as shown and described.

DESCRIPTION

FIG. 1 is a perspective view of a bicycle shoe embodying the design.

FIG. 2 is a right side view of the design shown in FIG. 1.

FIG. 3 is a left side view of the design shown in FIG. 1.

FIG. 4 is a front view of the design shown in FIG. 1.

FIG. 5 is a rear view of the design shown in FIG. 1.

FIG. 6 is top view of the design shown in FIG. 1; and,

FIG. 7 is a bottom view of the design shown in FIG. 1.

The portions of the bicycle shoe shown in broken lines form no part of the claimed design.

1 Claim, 7 Drawing Sheets
